UNITED STATES PATENT OFFICE.

JAMES KNEEN, 2d, OF BIRMINGHAM, AND WELLINGTON M. REED, OF HUNTINGTON, CONNECTICUT.

ESCAPEMENT MECHANISM FOR WATCHES.

SPECIFICATION forming part of Letters Patent No. 269,428, dated December 19, 1882.

Application filed April 11, 1882. (Model.)

To all whom it may concern:

Be it known that we, JAMES KNEEN, 2d, of Birmingham, in the county of New Haven and State of Connecticut, and WELLINGTON M. REED, of Huntington, in the county of Fairfield and State of Connecticut, have invented a new and useful Improvement in the Escape-
ment Mechanism of Watches, of which the following is a full, clear, and exact description.

Our invention relates to the ruby-pin tables of watches, with the object to allow adjustment of the tables and hair-spring of the balance-wheels without removal of the parts from places, as is required when the wheel and table are attached permanently to the pivot-shaft.

The invention consists in attaching the parts so that they can be adjusted in relation to each other on the staff, as hereinafter described and claimed.

Reference is to be had to the accompanying drawings, forming a part of this specification, in which similar letters of reference indicate corresponding parts in both the figures.

Figure 1 is a plan view of a staff and ruby-pin table, and Fig. 2 is a sectional side view of the same parts with the balance-wheel added.

A is the table, or "roller," as it is sometimes termed, fitted with ruby-pin *a*; *b*, the pivot-staff carrying the table, and C is the balance-

wheel, also on the staff. The wheel C is made 30 fast on the staff in the usual manner. The table A is held loosely on the staff between a collar, *d*, and a toothed wheel, *e*, and the table is provided with a spring pawl or pawls, *f*, that engage the teeth of the wheel, so that 35 there is friction enough to hold the table and cause its movement with the staff.

It will be readily seen that this construction permits adjustment of the ruby-table on the staff, so that in case the hair-spring of the 40 watch requires adjustment the staff need not be removed from its bearings. All that is necessary is to loosen one end of the spring, hold the ruby-table by the escapement-lever, and with the balance-wheel turn the staff one 45 or two teeth of the wheel *e*, as may be required.

Having thus described our invention, we claim as new and desire to secure by Letters Patent—

In a watch-escapement, the combination, 50 with the ruby-table A, the fixed toothed wheel *e*, and the pawl *f*, of the balance-wheel C and staff *b*, as shown and described.

JAMES KNEEN, 2d,
WELLINGTON MERRILL REED.
